UNITED STATES PATENT OFFICE.

JOSEPH PAUER AND EMIL BAHNIK, OF CLEVELAND, OHIO.

GRINDING-MACHINE.

1,252,162

Specification of Letters Patent. Patented Jan. 1, 1918.

Application filed April 14, 1917. Serial No. 161,944.

To all whom it may concern:

Be it known that we, JOSEPH PAUER and EMIL BAHNIK, citizen of the United States, residing at Cleveland, in the county of Cuyahoga and State of Ohio, have invented a certain new and useful Improvement in Grinding-Machines, of which the following is a full, clear, and exact description, reference being had to the accompanying drawings.

This invention relates to machines for accurately finishing the interior of cylindrical bores by grinding. The general object of the device is to provide a comparatively simple efficient mechanism for this purpose. A more specific object is to provide for conveniently placing the work in position to be operated upon and for readily removing the same when finished. Still another object is to so arrange the machine as to provide automatic mechanism for feeding the abrading member along the cylinder. Still other objects are to so arrange the work holding device that it may be quickly and accurately adjusted to bring the work to the proper position for operating, and also for adjusting the grinding member to finish the work to an accurate size.

The manner of accomplishing the above and other objects will appear in the following description which refers to the drawings, illustrating a preferred embodiment of our invention, and the essential characteristics are hereinafter set forth in the claims.

Referring to the drawings, Figure 1 is a perspective view of our machine; Fig. 2 is a vertical transverse section through the same; Fig. 3 is a vertical section on an enlarged scale through the spindle operating mechanism; Fig. 4 is a horizontal section through the same substantially on the line 4-4 of Fig. 3; Fig. 5 is a similar section taken on the plane indicated by the line 5-5 on Fig. 3; Fig. 6 is an enlarged sectional detail on the line 6-6 of Fig. 2; Fig. 7 is a sectional detail on the line 7-7 of Fig. 6; Fig. 8 is an axial section at the lower end of the spindle.

Describing the parts by reference characters, 1 designates a suitable supporting frame carrying a horizontal table 2 from which rise upright ways or guides 3 integral with diagonal supporting web-like braces 4.

Beneath the table 2 we have shown a transverse movable slide 5 having T-headed slots 6 engaged by guide bars 9 held by

screws 7 extending upwardly through elongated openings 8 in the table, whereby this slide is capable of a comparatively slight movement transversely of the slots 6 and may be slid throughout its length longitudinally of these slots and entirely removed from the screws 7, when desired. This slide is arranged to carry the work and accordingly is provided with an elongated opening 10 beneath a series of communicating partially circular openings 11 in the table 2, whereby a grinding wheel 12 carried on a spindle 14 may pass downwardly through these openings 10 and 11 and into a cylinder 15 for grinding the interior of the same to the desired size. The machine is particularly useful for grinding automobile cylinders, either for the first finishing or for regrinding after becoming worn. The several bores of the cylinder, arranged in one casting, may be successively presented to the grinding wheel by shifting the slide 5.

The spindle 14 is rotatably carried in a vertically movable head 20 having laterally extending wings 21 embracing the guides 3 and secured thereto by clamping plates 22 held to the wings 21 by cap screws 24. This head is given a vertical movement to feed the grinding wheel longitudinally of the cylinder by means of a screw 25 extending longitudinally between the ways 3 and embraced by a nut 26 secured by screws 27.

The spindle 14 comprises two members, a stiffening sleeve 30 and a driving shaft 32, each extending upwardly through the head 20. The driving shaft 32 is centrally positioned in this sleeve by suitable ball bearings, such as indicated at 33 at the upper end. At the lower end of the driving shaft 32, we provide a suitable non-friction bearing of bronze or like material, as indicated at 35. Below this bearing the shaft has a reduced portion forming a shoulder at the upper end of a threaded shank receiving a cup collar 38, which has a cylindrical portion adapted to receive the grinding wheel 12 adapted to be clamped thereon by a collar nut 37. The cup portion 38 is surrounded by the downwardly faced cupped extension 39 of the spindle 14. The cavity of this cup member is conical shaped to retain lubricant under rotation of high speed. At the upper end the bearing is shown as carried in a removable collar 34 threaded onto the upper end of the sleeve 30, while the shaft carries a pulley 36 threaded onto a

reduced portion and secured by a nut 37 for driving the grinding wheel 12 non-rotatably secured to the lower end of the shaft 32 which is thus stiffened by the sleeve 30.

5 The sleeve and shaft, comprising the spindle, are adapted to be adjusted to move its axis parallel to the axis of the cylinder, and to accomplish this, we provide a rotating cylindrical member 40 embraced by 10 adjustable bearing members 41 at the upper and lower ends of the head 20. This rotatable cylindrical member 40 carries guiding blocks 42 and 43 at the upper and lower ends respectively, and these blocks are provided with elongated openings 44 embracing the upper extension of the spindle in these openings.

15 To maintain the parallelism of the axis of the spindle with that of the sleeve 40, we provide carrying blocks 46 and 47, each pivoted on the ends of a vertical stud 48 and extending around and closely embracing the extension of the sleeve.

Both the upper and lower blocks 46 and 20 47 are provided with a segmental toothed portion 50 adapted to engage the upper and lower ends 52 and 53 of a vertical spindle 54 having its bearings in the blocks 42 and 43 and having teeth cut in its ends to form 25 pinions engaging these segmental portions. The rotation of this rod 54 causes the blocks 46 and 47 to swing about the ends of the stud 48 as pivots. The toothed ends of the rod 54 preferably closely fit the teeth 50, 30 so that an accurate adjustment of the axis of the spindle with relation to the axis of the sleeve 40 may be obtained. To secure such adjustment and to insure holding the spindle in any position given it, we have 35 shown a worm 55 mounted in bearings 56 on an outwardly extending flange on a head 58 of the sleeve 40. The worm 55 is shown as having an angular head 57 by which it may be rotated to rotate the rod 54 and adjust the 40 axis of the spindle with relation to the axis of the sleeve 40.

The reason for adjusting the axis of the spindle with relation to the sleeve 40 is to bring the grinding surface of the wheel 12 45 into contact with the cylinder to be finished. The grinding of the cylinders is accomplished by causing the axis of the rapidly rotating grinding wheel to revolve in a circular path in contact with the inner 50 surface of the cylinder, at the same time advancing the wheel longitudinally of the cylinder. The advancing movement is caused by the screw 25 heretofore described.

To give the axis of the wheel its revolving 60 motion about the axis of the cylinder, causing it to travel circumferentially about the cylinder and contact with its surface or spindle, after being adjusted to present the periphery of the grinding wheel to the surface 65 of the cylinder by moving the axis of the

spindle with relation to the sleeve 40, we provide gear teeth 60 on a flange head 58 of the sleeve 40. Meshing with these teeth is a pinion 68 surrounding a shaft 63 and resting on a web 64 integral with the head. 70 This pinion is provided with clutch teeth 65 engaged by corresponding teeth on a movable clutch member 66 splined to the shaft 63 so that it may be driven thereby in any position along the same. This clutch member may be thrown in and out of engagement with the teeth of the pinion by a yoke lever 67 having pins 68 engaging a circumferential groove 69. The shaft 63 is provided with removable bearings in the web 80 64 and in a web 61, whereby it is guided by the head to insure proper engagement of the gear teeth 60 and pinion 62, while a bearing carried by a bracket 90, embraces this shaft at the lower end.

To rotate the spindle 32 and the wheel 12, we may use a belt 75 running over the pulley 36 at the upper end of the shaft 32, as heretofore described. This belt 75 may be brought to the pulley 36 from any direction 90 and be arranged to remain tight by a suitable belt tightener, allowing for the revolving movement of the pulley, while causing its rotation; but we prefer to lead the belt 75 laterally between the uprights 4 and each 95 side of the screw 25 and then upwardly, guiding it by flanged pulleys 77 carried on brackets 78 secured to the head, thus causing the belt to be presented to the pulley 36 at the proper angle regardless of the position 100 of the head.

We have shown, as a means for rotating the shaft 63 and the screw 25, a belt 80 running over a stepped pulley 81 on a shaft 82 carried in a bracket 83 secured to the top of the uprights 4. On the inner end of the shaft 82 we provide a bevel gear 85 meshing with bevel gears 86 and 87 at the upper and lower sides respectively and each loosely mounted on a shaft-like extension of the 110 screw 25. The bevel gear 87 is rigid with a spur gear 88 which meshes with an idler 89 in turn driving a gear 90 rigid on the upper end of the shaft 63. Thus the gear unit 87-88 is driven continuously by the belt 80, 115 causing a constant rotation of the shaft 63, while the revolution of the grinding wheel spindle may be stopped or started by actuating the clutch lever 67 connecting the shaft 63 with the gear 60, as heretofore described. 120

The upper bevel gear 86 is for the purpose of driving the screw 25 in one direction only and may be brought into driving connection by means of a splined clutch member 92 having teeth at opposite sides adapted 125 to engage either the teeth 93 of the gear 86 or the teeth 94 of the gear 87. The clutch member is rotatably embraced by a yoke arm 95 for causing this movement and the yoke arm is in turn connected with a vertically 130

movable rod 96, guided through an ear formed on the bracket 82 and rigidly connected by a transverse arm 97 with a vertical rod 98. The rod 98 is guided through webs 71 and 74 on the head corresponding to the webs 61 and 64 and this rod carries adjustable collars 100 adapted to be engaged by these webs to cause the shifting of the clutch member 92 to stop or reverse the direction of rotation of the screw consequent upon the grinding wheel reaching a predetermined point.

Referring to the means for centering the cylinder bore with relation to the axis of the sleeve 40 and the movement of the wheel, the plate 5 carrying the cylinder, is movable in both directions, the slots 8 providing for lateral movement and the engagement of the T-slots with the longitudinal strips 9 allowing longitudinal movement. To cause such movement with considerable accuracy thereby providing for adjustment, we have shown a pinion 105 engaging a rack 106 at the lower side of the plate 5. The pinion is carried on a spindle 107 and adapted to be rotated by a hand wheel 108. The rack 106 is considerably wider than the pinion, to provide engagement irrespective of lateral shifting of the plate.

The lateral shifting may be caused by a screw 110 actuated by a hand wheel 111 and engaging a slide 112 mounted in a transverse slot underneath the plate 32. The slide is shown as having a threaded boss engaging the screw 110 and a downturned end 114 engaging the upper portion of the T-slot 6. Thus, this projection remains in engagement with the slot and may move the plate irrespective of its position.

The opening 11 in the plate 2 is shown as formed by three partially circular openings, each of which is as large or larger than the cylinder to be ground, thus giving access to the cylinder bore at either side of the one being operated upon, for purposes of caliper, cleaning, etc.

Briefly, the operation of our device is as follows: The cylinder 15 is secured by cap screws to a plate 5, preferably removed from the machine. The plate is then placed in position upon the slide bars 9 and then the hand wheels 108 and 111 are actuated to position the same approximately centering one of the cylinders. The screws 7 are then tightened. A suitable grinding wheel for the cylinder to be operated upon having been fitted to the lower end of the spindle, the belts 50 and 75 started, the head and grinding wheel are lowered by manually shifting the clutch 92 from its controlling rods into engagement with the bevel gear, causing a rotation of the screw 25 in a direction corresponding to such movement.

As the grinding wheel is thus brought into the end of the cylinder, the spindle is ad-

justed by means of the worm and pinion rod 53, to present the periphery of the wheel to the cylinder. The clutch 92 is then thrown into engagement to cause the revolution of the grinding wheel, thus starting the operation. The amount of metal to be removed during one movement of the wheel along the cylinder having been determined, the clutch 92 is again operated to continue the downward movement. The lower collar 100 is adjusted to accommodate the length of the cylinder, and upon the grinding wheel reaching the lower end of the same, the web 71 engaging this collar shifts the clutch 92 into engagement with the lower bevel gear 87, thus reversing the motion of the screw and withdrawing the wheel 14. This operation may be continued several times for each cylinder until the proper amount of metal has been removed, the successive cylinders being presented to the grinding wheel by operating the handle 108 after slightly loosening the screws 7 to shift the plate 5 the proper distance.

It will be seen from the foregoing description that we have provided a comparatively simple machine for grinding cylinders with a single grinding wheel, given three movements, namely, a rotative movement on its own center, a revolving movement of the axis thereof about the axis of the cylinder, and a progressive movement longitudinally thereof, and that we have provided a simple and convenient means for causing all of these movements in connection with easily operated partially automatic devices controlling such means.

Having thus described our invention, what we claim is:

1. In a cylinder grinding machine, the combination of a housing, a rotatable cylinder therein, a spindle extending through the cylinder with its axis parallel to that of the cylinder, bearings at each end of the cylinder movably connected therewith, a longitudinal shaft carried by the cylinder and geared with said bearings for simultaneously shifting the same, and means for turning said last named shaft.

2. In a cylinder grinding machine, the combination of a housing, a rotatable cylinder therein, end members rigid with the cylinder, a spindle extending through said members with its axis parallel to the cylinder, bearings embracing the spindle at separated points, means carried by the end members for laterally shifting said bearings simultaneously including a longitudinal member geared to the bearings, and a screw for actuating the longitudinal member to simultaneously move said members.

3. In a cylinder grinding machine, the combination of a work support, guideways projecting therefrom, a head movable along said guideways, a spindle carried by said

4
head and adjustable eccentrically thereof, a screw for advancing the head, a shaft parallel to the spindle, a gear for causing the revolution of the spindle, a gear for driving the same splined to said shaft, means for rotating the shaft and screw, and separate means for rotating the spindle.

5. In a cylinder grinding machine, the combination of a work holding plate, a table 10 supporting the same, means for securing the table to the plate including parallel guides, means for adjustably holding the guides to the table, means causing a movement of the work holder transversely of the 15 guides, a rack and pinion for causing movement longitudinally of the guides, a spindle carrying head, guideways for the head, means for moving the head along said guideways, means for revolving the spindle eccentrically of the cylinder, and independent 20 means for rotating the spindle on its own axis.

6. In a cylinder grinding machine, the combination of a housing, a rotatable cylinder 25 therein, a transverse partition in said cylinder having a slot, a spindle extending through said cylinder with its axis parallel with the axis of the cylinder, a bearing embracing the spindle and movably carried by 30 the cylinder to permit movement of the spindle in the slot, and means for accurately adjusting the spindle in eccentric relation to the cylinder.

7. In a cylinder grinding machine, the combination of a housing, a rotatable cylinder 35 therein, a spindle extending therethrough, end members rigid with the cylinder, bearing members for the spindle pivoted to the end members, said end members 40 having slotted openings permitting lateral shifting of the spindle in parallel relation to the cylinder, and means for simultaneously shifting the bearings.

8. In a cylinder grinding machine, the combination of a housing, a hollow cylinder 45

drical member rotatably carried therein, end walls rigid with said cylinder, a spindle extending therethrough, said end walls having enlarged openings permitting lateral movement of the spindle, bearing members closely 50 embracing the spindle at each end of the cylinder and pivoted to said end walls, an operating member for laterally shifting said bearing members simultaneously extending through said cylinder and engaging each 55 of the bearing members, and a screw device for actuating said operating member to accurately adjust the spindle.

9. In a cylinder grinding machine, the combination of a frame comprising a table 60 and guideways at right angles thereto, a traveling head on said guideways, a spindle carried by said traveling head and adjustable in eccentric relation thereto, a work support, parallel ways on which the work 65 support is slidable, means securing said ways to the table, means for sliding the work support along the ways, and means for laterally shifting the ways with relation to the table.

10. In a cylinder grinding machine, the combination of a table and ways at right angles thereto, of an operating head 70 slideable along the ways, a spindle carried by the head and adjustable in eccentric relation 75 thereto, means for rotating the spindle and means for moving the head along the ways, a work support having parallel slots, ways engaging said slots, means securing the ways to the table extending through elongated 80 openings, a screw for laterally moving the ways and work support with relation to the table, and means for moving the work support along the ways, said table having openings permitting access to the cylinder, secured to the work support.

In testimony whereof we hereunto affix our signatures.

JOSEPH PAUER
EMIL MAHNIK.
